Application February 16, 1938, Serial No. 190,832
In Great Britain February 18, 1937

20 Claims. (Cl. 178—44)

This invention relates in general to wave transmission systems, but more particularly, though not exclusively, to electric signal transmission systems.

5 The properties of any wave transmission path in which in a specific frequency range the constants are substantially smoothly distributed are known when the complex propagation constant

$$P = \alpha + j\beta = \sqrt{(R + j\omega L)(G + j\omega C)}$$

10 is determined for all frequencies within the specified range, where α is the attenuation constant and β the phase constant and R , L , G and C are respectively the resistance, inductance, 15 leakance and capacity of the transmission line per unit length and ω is the angular frequency of the signals being transmitted. If the attenuation constant α is independent of frequency then all oscillations caused to travel over the 20 path will do so without the occurrence of variations in relative amplitude. If also the phase constant β is proportional to ω so that the time delay

$$\frac{d\beta}{d\omega}$$

25 is constant, then relative phases will also be transmitted undisturbed.

In general, with a cable or transmission line, 30 these conditions are not satisfied and it is therefore necessary to employ equalising or compensating circuits whereby the attenuation constant is made substantially independent of frequency and the phase constant substantially directly 35 proportional to frequency over the frequency range of the signals transmitted along the transmission line or cable. The variation with frequency of the attenuation and phase of the transmission line or cable arises either due to the variation with frequency of the effective resistance and inductance of the cable or the effective capacity and leakance of the cable or due to variation of all of these constants. In telephony, 40 however, variations in phase are relatively unimportant, so that the equalising circuits are provided mainly for the purpose of correcting the attenuation or loss characteristic. Some effect on phase is always introduced by the use of such circuits, but this is purely arbitrary so that if 45 it is desired to correct for phase the addition of phase-correcting circuits is necessary. If such phase-correcting circuits are used it may be found that the loss will have to be corrected again, and so on. Such methods of correction 50 therefore are generally those of trial and error

and the compensation that is obtained is usually subject to random errors.

In transmitting a wide frequency range of signals along a cable, such as television signals which may extend from zero frequency up to some megacycles per second, the problem is considerably more complex. Not only are variations in amplitude particularly important, but relative phases in addition may be allowed to vary only within very small limits. In an actual high frequency cable, owing to the skin effect in the conductors, the resistance of the cable increases with frequency and the inductance falls. Further, owing to the fact that the capacity of the cable acts not like an ideal condenser but like a somewhat complicated network of condensers and resistances, the capacity tends to decrease slightly and the leakance to rise as the frequency rises. With such a cable it will be apparent that since all four primary constants will vary with frequency, the attenuation constant will vary with frequency and the phase constant will not be proportional to frequency. Distortion of the signals transmitted along such cable both in amplitude and phase will therefore result. The use of equalising and compensating means is therefore necessary to reduce the distortion. However, the use of the methods of correction previously referred to, which necessarily involve the introduction of random effects, is of little value since the random effects may total to a magnitude of considerable extent, especially over a long length of cable.

The present invention is primarily concerned 35 with the simultaneous equalisation of the attenuation and phase of a cable or transmission line designed to handle a wide frequency band of signals, but as will be apparent hereinafter, the invention is capable of a much wider application.

In this specification and in the appended 40 claims, what is meant by equalisation of attenuation and phase is that the attenuation constant is made substantially independent of frequency and the phase constant is made substantially directly proportional to frequency over the range 45 of frequencies for which equalisation is effected.

It is known that where oscillations, such as 50 mechanical or acoustical oscillations, are required to be transmitted, similar difficulties are encountered due to the attenuation and phase of the transmission path and it is also well known that the analogues of resistance, inductance, capacity and leakance exist in the mechanical and acoustical cases. The present invention is also 55

applicable to mechanical and acoustical transmission systems.

The object of the present invention is to provide an improved transmission system in which the variation of loss and phase due to variation with frequency of the effective resistance and inductance or capacity and leakance, or both, (or their analogues) is simultaneously equalised and in which the equalisation is effected with considerably reduced random errors.

Various forms of equaliser sections for electrical signal transmission lines have been proposed comprising combinations of inductance and capacity or resistance arranged so as to produce the complement of the variation of attenuation and phase introduced by a cable, but with such equalisers it was necessary to equalise loss and phase separately.

The present invention can be employed with any suitable type of equaliser section providing that the equaliser sections employed produce similar characteristic curves such as can be expressed as a function of

$$\frac{p}{\omega}$$

where p is an angular frequency defined in the same way for all sections employed and ω is the angular frequency at which the property whose behaviour characterised by the curves is evaluated. This implies that the zero frequency loss for all sections is the same. The frequency p will hereinafter and in the appended claims be referred to as the "reference frequency". In sections of the simple type comprising series arms composed of resistances shunted by condensers and shunt arms composed of inductances in series with resistances a convenient reference frequency to take is that frequency at which the reactance of each arm becomes equal to its associated resistance. In more complicated types in which several reactances and resistances may be employed the reference frequency may be taken as that at which some particular reactance becomes equal to some particular resistance. It will be found that the reference frequency will always correspond to a value at which the loss of the section has fallen to a certain fraction of its maximum value. The reference frequency may therefore be regarded as that angular frequency at which the loss of the section has fallen to some arbitrarily chosen fraction of its maximum value, which fraction is substantially constant for all sections. The present invention is based upon the principle of arranging the equaliser sections in such a manner that their reference frequencies are spaced at values corresponding to substantially equal increments of variation of the transmission path. By employing such a principle it is possible to equalise a cable without the introduction of serious random errors, provided, for example, that the loss curve of the path can be resolved into one or more component curves of the form $A_n \omega^n$, or that the phase curve of the path can be resolved into one or more component curves of the form $B_n \omega^n$; moreover, if the cable is such that the type

$$B_n = A_n \tan \frac{n\pi}{2}$$

are satisfied, then simultaneous equalisation of loss and phase delay is achieved.

In general the principle of equal spacing may be applied to equalise distortion arising from any frequency characteristic which may be expressed as a finite power series in frequency.

Accordingly, the present invention broadly comprises a wave transmission system including a transmission path with substantially smoothly distributed constants along which oscillations extending over a range of frequencies are caused to travel, and in which the path is such as to cause distortion of the oscillations which varies with the frequencies of the respective oscillations owing to the variation with frequency of the effective resistance and inductance or the capacity and leakance, or both (or their analogues), and in which the characteristic curve of the cable can be analysed into the form mentioned above and wherein a compensating or equalising path is associated with said transmission path comprising a plurality of equaliser sections the reference frequencies of which are spaced at values corresponding substantially to equal increments of variation on the component curve or curves of the transmission path, said sections being designed in such a manner, in conjunction with their spacing, as to produce substantially the complement of the increment of variation so that the loss and phase distortion due to variation with frequency either of effective resistance and inductance or of capacity and leakance, or both, are simultaneously equalised.

More specifically, the invention is concerned with the case in which the path is such as to cause attenuation and phase distortion of the oscillations and in which the reference frequencies of the equaliser sections are located at frequencies corresponding substantially to equal increments of loss of the component curve or curves of the transmission path and designed in such a manner that the loss of the transmission path is made substantially independent of frequency and the phase constant substantially directly proportional to frequency.

The present invention is especially applicable to an electric signal transmission system which is designed for the transmission of signals extending over a very wide frequency range extending at least up to 100 kilocycles per second. The invention is also applicable to the case in which the transmission line is designed for the transmission of frequencies from substantially zero frequency up to about two or three megacycles per second, such latter frequencies being ordinarily encountered in the transmission of television signals. When dealing with signals extending over such a wide range of frequencies the variation of attenuation and phase is due to variation with frequency of all four primary constants of the cable and the present invention can accordingly be applied to such a system for equalising simultaneously the greater part of the variation of the loss and phase. The invention may also be applied to transmission lines or cables transmitting signals extending over much smaller frequency ranges. It may also be employed in a transmission line or cable for equalising the effect only of variation with frequency of the resistance and inductance or capacity and leakance. It is also possible to apply it to a cable in which the equalisation is effected by loading the cable at intervals along its length, which intervals are short compared with the wavelength of the highest frequency to be transmitted or to the case in which an arbitrary length of cable or transmission line is equalised as a whole by the use of a plurality of equaliser sections.

In all cases the reference frequencies of the equaliser sections will be located at frequencies corresponding to equal increments in the varia-

tion of the transmission path and, subject to certain conditions hereinafter to be referred to, any type of equaliser section may be employed in the invention. The invention preferably employs 5 equaliser sections of the so-called constant resistance type but is not limited in scope to the use of such sections.

In order that the said invention may be clearly understood and readily carried into effect the 10 same will now be more fully described with reference to the accompanying drawing in which:

Figure 1 illustrates the manner in which the loss of a cable, such as might be employed for television purposes, varies in the range from 15 zero frequency to frequencies of several megacycles per second.

Figures 2, 3 and 4 illustrate networks which may be employed in the invention, and

Figure 5 illustrates an improved type of equaliser section according to a feature of the invention.

The invention will now be described more fully and as applied to a transmission line or cable in which variation of the four primary constants 25 of the cable occurs with variation in frequency and in which it is desired to equalise simultaneously the greater part of the loss and phase due to the variation of these four primary constants.

Figure 1 illustrates a typical loss curve of a cable. In order to avoid a relative variation in the amplitude of signals at various frequencies transmitted along a cable having such a characteristic, it is necessary, as stated above, to employ 30 an equaliser which may take the form of loading at intervals along the length of the cable but more conveniently the equaliser is in the form of an artificial line inserted in series with the cable at a convenient point before or after suitable amplifiers. The equaliser is 35 designed to produce the complement of the loss produced by the cable so that when the equaliser is connected to the cable the overall loss is substantially constant over the frequency range for 40 which the equaliser is designed. It has been found that an equaliser of the form described here which is designed to make the overall loss of a cable substantially independent of frequency 45 simultaneously makes the phase constant directly proportional to frequency.

The sections of an equaliser constructed in accordance with the invention are arranged so that their reference frequencies, as hereinbefore defined, are spaced at values corresponding substantially to equal increments of loss of the cable. As shown in Figure 1, the angular frequency $p_1, p_2, \dots$, correspond to substantially equal increments in loss of the cable characteristic. The equaliser designed in accordance 50 with the invention has the reference frequencies of the sections arranged so that they are equal to $p_1, p_2, \dots$.

In the following explanation of the invention it will be shown how the proper spacing of the angular frequencies $p_1, p_2, \dots$, may be determined. The equaliser sections employed produce similar characteristic curves as stated above, such as can be expressed by a function of

70
$$\frac{P}{\omega}$$

Let $f(q)$ where
$$q = \frac{P}{\omega}$$

75 P being the reference frequency, be the variable

part of the loss at frequency ω due to any one of a number of like sections so that the variation of loss due to all the sections may be expressed as

$$f\left(\frac{p_1}{\omega}\right) + f\left(\frac{p_2}{\omega}\right) + f\left(\frac{p_3}{\omega}\right) + \dots \quad 5$$

If the difference $p_2 - p_1, p_3 - p_2, \dots$, all correspond to equal small increments x in a loss characteristic $F(\omega)$ such as the loss curve shown in Figure 1, and if the loss introduced by a section at any frequency is small compared with the cable loss to be equalised at that frequency, then the method of the integral calculus may be employed to evaluate this sum. Thus in the range of angular frequency dp there will be located 15

$$\frac{1}{x} F'(p) dp \text{ sections}$$

where a dash signifies a first differentiation, and due to this number of sections there will be contributed an amount of loss at a frequency ω equal to 20

$$\frac{1}{x} F'(p) f\left(\frac{p}{\omega}\right) dp \quad 25$$

The total loss at this frequency is, therefore,

$$\frac{1}{x} \int_0^\infty F'(p) f\left(\frac{p}{\omega}\right) dp \quad 30$$

The sections will accordingly possess the same total loss characteristic as the curve along which they have been distributed if

$$\frac{1}{x} \int_0^\infty F'(p) f\left(\frac{p}{\omega}\right) dp = F(\omega) \quad 35$$

This can be shown to lead to a finite value of x if $F(\omega)$ is of the form $A\omega^n$. It is in fact then found directly that

$$x = n \int_0^\infty q^{n-1} f(q) dq$$

Turning now to a consideration of the phase characteristic that will be obtained with this distribution let $\phi(q)$ represent the phase characteristic of any one section. Performing an integration in the same way as before the total phase at an angular frequency ω will be 45

$$\begin{aligned} \Phi(\omega) &= \frac{1}{x} \int_0^\infty F'(p) \phi\left(\frac{p}{\omega}\right) dp = \\ &= A \omega^n \int_0^\infty q^{n-1} \phi(q) dq \\ &= - \frac{1}{\int_0^\infty q^{n-1} f(q) dq} \end{aligned} \quad 55$$

Subject, therefore, to a consideration of the finiteness of these integrals it appears that if in the loss characteristic of a network constructed as herein supposed there occurs a term ω^n in the loss characteristic, then there will also occur a term ω^n in the phase characteristic. This is a completely fundamental relation for all equalisers having sections possessing similar characteristic curves and spaced as stated above, since it is independent of the forms of $f(q)$ and $\phi(q)$. 60

In order to determine the conditions of finiteness for the integrals

$$\int_0^\infty q^{n-1} f(q) dq \quad 75$$

and

$$\int_0^\infty q^{n-1} \phi(q) dq$$

- 5 it is necessary to consider special cases, since such conditions will clearly depend on the special forms of $f(q)$ and $\phi(q)$. The special case of a constant resistance section will be selected for purposes of illustration but it will be understood that the invention is not limited in its use to the constant resistance type of section.

10 It is necessary for this problem to determine the propagation constant as a function of q since the propagation constant has already been supposed to possess a variable real part $f(q)$ and an imaginary part $\phi(q)$. Now in a constant resistance section, by which is meant a section possessing a series arm of impedance Z_1 and a shunt arm of impedance Z_2 , such that $Z_1 Z_2 = Z_0^2$, 15 and having an additional resistance Z_0 connected either across the series arm or in series with the shunt arm, the current ratio k , as is well known, 20 is given by

$$25 \quad k = 1 + \frac{Z_0}{Z_2}$$

In terms of k , the propagation constant is simply given according to

$$e^{P(q)} = k$$

- 30 It is therefore necessary to express Z_2 as a function of q , and it has been found possible to do this in a very general manner by a process of building up any impedance from elementary impedances comprising either resistance in series with inductance, resistance in parallel with inductance, 35 resistance in series with capacity or resistance in parallel with capacity. By this method it may

40

be shown that any impedance Z can be put in the form

$$45 \quad Z = \frac{g_1(q+ja_1)g_2(q+ja_2) \dots}{(q+jb_1)(q+jb_2) \dots}$$

50 where $g_1, g_2, \dots, a_1, a_2, \dots, b_1, b_2, \dots$ are real constants which occur if the impedance of an arm or if a current ratio is expressed in this form and where, as before stated,

$$q = \frac{P}{\omega}$$

55 P being a constant frequency as defined in any arbitrary way and as stated in the so-called reference frequency.

By virtue of this fact it is possible to write for k the very general expression

$$60 \quad \frac{s_1(q+jt_1)s_2(q+jt_2) \dots}{g_1(q+ja_1)g_2(q+ja_2) \dots}$$

where $s_1, s_2, \dots$, and $t_1, t_2, \dots$, are further real constants of the kind as referred to above. For convenience this form will be contracted to:

$$65 \quad \frac{Q(s)Q(q+jt)}{Q(s)Q(q+ja)}$$

by using the notation $Q(z) = z_1, z_2, z_3, \dots$. It follows directly from this form that

$$70 \quad f(q) = \frac{1}{2} \sum \log \frac{q^2 + t^2}{q^2 + a^2}$$

$$\phi(q) = \sum \tan^{-1} \frac{t}{q} - \sum \tan^{-1} \frac{a}{q}$$

In passing, and before proceeding to employ these derivations it may be pointed out that as ω tends

to zero the value of the attenuation constant tends to

$$\Sigma \log \frac{s}{g}$$

i. e., to

$$\log \left\{ Q \left(\frac{s}{g} \right) \right\}$$

and that as ω tends to infinity the attenuation tends to

$$\Sigma \log \frac{st}{ga}$$

i. e., to

$$\log \left\{ Q \left(\frac{s}{g} \right) \frac{Q(t)}{Q(a)} \right\}$$

so that if $Q(t) > Q(a)$ then the attenuation at infinite frequency is greater than that at zero frequency. It $Q(t) < Q(a)$ then the attenuation at finite frequency is less than that at zero frequency. Thus by adjusting the relative values of $Q(t)$ and $Q(a)$, it is possible to give the attenuation curve of the section a general rise or a general fall over the whole frequency range from zero to infinity. The curve over any particular part of the frequency range, however, may rise or fall according to values of the individual terms $(q^2 + t^2)$ and $(q^2 + a^2)$.

In proceeding to consider the previously mentioned integrals it is permissible to deal with each term in $f(q)$ and $\phi(q)$ separately. Thus corresponding to the general term in $f(q)$ there is the integral

$$35 \quad \frac{1}{2} \int_0^\infty q^{n-1} \log \frac{q^2 + t^2}{q^2 + a^2} dq = \frac{1}{2} \int_0^\infty q^{n-1} \left(\frac{t^2 - a^2}{q^2 + a^2} - \frac{1}{2} \frac{(t^2 - a^2)^2}{(q^2 + a^2)^2} + \dots \right) dq$$

$$= \frac{1}{2} \left((t^2 - a^2) \int_0^\infty \frac{q^{n-1} dq}{q^2 + a^2} - \frac{(t^2 - a^2)^2}{2} \int_0^\infty \frac{q^{n-1} dq}{(q^2 + a^2)^2} + \dots \right) 40$$

Now it can be shown that

$$\int_0^\infty \frac{x^a dx}{x^b + c}$$

is finite provided $b-1$ exceeds a . Applying this result to the first integral in the expansion, since this term constitutes the greatest restriction on n , it follows that $n-1$ must be less than unity, and, therefore, that n must be less than two.

50 By a similar procedure it may be shown that

$$\int_0^\infty q^{n-1} \phi(q) dq$$

55 is finite for all values of n less than unity.

Also if n is less than unity it can be shown that

$$60 \quad \frac{\int_0^\infty q^{n-1} \phi(q) dq}{\int_0^\infty q^{n-1} f(q) dq} = \frac{\sin \frac{n\pi}{2}}{\cos \frac{n\pi}{2}}$$

For $n = \frac{1}{2}$ this becomes

$$\frac{\sin \frac{\pi}{4}}{\cos \frac{\pi}{4}} = 1$$

The following conclusions are therefore to be drawn:

(a) If the power of ω is two or over the spacing factor x is infinite, so that in practice an equaliser of this type cannot be produced so as to possess

75

a loss varying as a power of ω equal or greater than two:

(b) If the power of ω is equal or greater than unity the phase becomes infinite at all frequencies:

(c) For powers of ω less than unity a term $A\omega^n$ in the attenuation is accompanied by a corresponding term

$$10 \quad A \frac{\sin \frac{n\pi}{2}}{\cos \frac{n\pi}{2}} \omega^n$$

in the phase.

Considering now the expression for $f(q)$ it will be clear that for every constant resistance network obtained in the manner that has been described above and having an attenuation component given by $A\omega^n$ there is always a complementary network having a component equal to the negative of this term, to be obtained by an interchange of the respective constants t_1, t_2 , etc., and a_1, a_2 , etc. Moreover, if the first network possesses a phase characteristic with a component $B_n\omega^n$ this interchange produces a network with a component $-B_n\omega^n$. Thus, by putting these two networks together in series the resultant loss will be constant and there will be no phase distortion. If, therefore, the cable has such characteristics that any variation of loss can be represented by a series of terms: $A_1\omega^{n_1} + A_2\omega^{n_2} + \dots$ and such that the variation of phase can be represented by a corresponding series of terms:

$$35 \quad A_1 \frac{\sin \frac{n_1\pi}{2}}{\cos \frac{n_1\pi}{2}} \omega^{n_1} + A_2 \frac{\sin \frac{n_2\pi}{2}}{\cos \frac{n_2\pi}{2}} \omega^{n_2} + \dots$$

40 it follows that it can be equalised by a structure of the type described here.

From the above it will be appreciated that by constructing an equaliser having the reference frequencies of its sections spaced at values corresponding to substantially equal increments of loss, the loss and phase distortion of a cable can be simultaneously equalised.

It is necessary now to consider the limitations that must be imposed on the sections employed in the equaliser. It has already been stated that the loss of a single equaliser section must be small compared with the loss required to be equalised. Since the loss characteristic of a cable is one which rises with frequency it is clear that the characteristic of a single section must fall with increasing frequency. Hence $Q(a)$ must exceed $Q(t)$ and it follows that the impedance of the shunt arm must tend to a limit at infinite frequency which is larger than its value at zero frequency.

It follows that the impedance of the shunt arm must never be zero at finite frequencies since otherwise infinite attenuation would result. In particular, it must not be zero at zero frequency.

The corresponding conditions for the series arm follows of course from the relation $Z_1 Z_2 = Z_0^2$.

Having now indicated in some detail the nature of the methods by which variations in a transmission line may be compensated for, by showing how they may be employed to counteract variations in total loss and phase it will now be shown how they may be applied to equalise directly variations in inductance and resistance or capacity and leakance in a short length of line,

i. e., short compared with the shortest wavelength transmitted.

It may be shown by experiment or by calculation that the variations of resistance and inductance, which are the components introducing distortion into the transmission, are represented with sufficient accuracy for frequencies greater than 50,000 cycles per second by a term $\omega^{\frac{1}{2}}$ and $\omega^{-\frac{1}{2}}$ respectively. Now a resistance varying like $\omega^{\frac{1}{2}}$ is provided by a chain of parallel connected resistance and inductance elements such as is shown in Figure 2. Thus, suppose the resistance elements are all the same and of magnitude equal to R , then the impedance of any one element in the chain is

$$\frac{Rj\omega L}{R+j\omega L}$$

from which it follows that the total effective resistance of the whole chain is the sum of all such terms as

$$\frac{R}{1+q^2}$$

where

$$q = \frac{p}{\omega}$$

p being that angular frequency at which the reactance becomes equal to the resistance. Performing this summation it is found that any resistance variation like $A\omega^n$ may be obtained if the distribution of elements is made by equal increments x in resistance where

$$35 \quad x = nR \int_0^\infty \frac{q^{n-1} dq}{q^2 + 1}$$

This spacing gives rise to a reactance term

$$40 \quad A\omega^n \int_0^\infty \frac{q^n dq}{q^2 + 1}$$

and therefore to an inductance term

$$50 \quad A \frac{\sin \frac{n\pi}{2}}{\cos \frac{n\pi}{2}} \omega^{n-1}$$

Hence a chain of elements of this type can, with a distribution at increments x , be used to simulate the variations of resistance and inductance in the cable.

But it is a simple matter to show that a resistance R_1 connected in parallel to an inductance L , the combination forming a series element, may be replaced by a shunt element of the type appearing in Figure 3 comprising a resistance R_2 connected in series with a capacity C if

$$\frac{L}{C} = R_1 R_2 = Z_0^2$$

Thus it is possible to simulate the variations of resistance and inductance by a number of suitably distributed shunt elements formed by capacities in series with resistances. As a further possibility the same effect may be obtained by a combination of the two types of simulating elements to give a network which possesses sections having a characteristic impedance Z_0 . Such a network illustrated in Figure 4.

Since this network reproduces exactly the effect of the variations in resistance and inductance it

follows that it reproduces exactly the variations in loss and phase that occur in the cable due to these variations of resistance and inductance. Now the loss of a single section of this network is

5

$$\alpha(q) = \sqrt{\frac{R_1}{R_2}} \left(\frac{1}{1+q^2} \right)$$

so that the total loss at an angular frequency ω of the network is

10

$$\frac{A\omega^n}{\sqrt{R_1 R_2}}$$

But the analysis given earlier showed that such a loss characteristic could be provided by a suitable distribution of any type of section subject only to certain limitations. The cable may therefore be regarded merely as an infinitely finely distributed example of one of the types of structures discussed earlier. By the provision of a complementary structure it is therefore possible to cancel the distortion that arises from variations in inductance and resistance. The effect of variations in capacity and leakage inductance may, using a similar argument, be shown capable of elimination by the same general method.

In compensating for variations by any of the above methods it is not necessary for the construction of an equalising network to be based on the use of a single spacing factor x . It is possible to split up such a network into a plurality of subsidiary structures, each with its own spacing factor provided a certain condition is satisfied by the spacing factors $x_1, x_2, \dots$ of these subsidiary structures.

Thus, suppose sections possessing a characteristic $f(q)$ are utilised, then by means of a spacing factor x_k it is possible to provide a characteristic like

40

$$\frac{nA\omega^n}{x_k} \int_0^\infty q^{n-1} f(q) dq$$

A plurality of structures each with their own particular value of x_k when connected in series are therefore capable of producing a characteristic expressed by

45

$$\sum_k \frac{nA\omega^n}{x_k} \int_0^\infty q^{n-1} f(q) dq$$

This may be set equal to

50

$$\frac{nA\omega^n}{x} \int_0^\infty q^{n-1} f(q) dq$$

if

$$\frac{1}{x} = \sum_k \frac{1}{x_k}$$

It will be clear that there is an even more general equivalence than this, for if in the k th subsidiary section a characteristic $f_k(q)$ is employed, in the $(k+1)$ th a characteristic $f_{k+1}(q)$, and so on for all the rest, it will still be possible to simulate the effect of a characteristic $f(q)$ with a spacing factor x if

55

$$\frac{1}{x} = \frac{1}{J} \sum_k \frac{J_k}{x_k}$$

where

60

$$J_k = \int_0^\infty q^{n-1} f_k(q) dq$$

and of course

65

$$J = \int_0^\infty q^{n-1} f(q) dq$$

The evaluation of spacing factors may be effected from the formula

$$x = \frac{\pi}{2} \sum \cos \frac{n\pi}{2}$$

5

where the $a_1, a_2, \dots$, and $t_1, t_2, \dots$, are the constants that appear in the expression

$$f(q) = \frac{1}{2} \sum \log \frac{q^2 + t^2}{q^2 + a^2}$$

10

In deriving the above expression for x it was found convenient to utilize an alternative integral form for x

$$x = \int_0^\infty q^n f(q) dq$$

15

This may be obtained by calculating the total slope of the equalizer characteristic at an angular frequency ω and setting it equal to the negative of the slope of cable at ω .

When $n = \frac{1}{2}$

$$x = \frac{\pi}{\sqrt{2}} \sum \left(\sqrt{a} - \sqrt{t} \right)$$

25

It will be appreciated that so long as the loss and phase curve for the cable or transmission line can be analyzed into the form stated above, and providing the equalizer sections meet the requirements hereinbefore referred to, any suitable type of section may be employed.

It will thus be appreciated that there is a large number of equalizer sections which are capable of equalizing simultaneously the loss and phase of a cable due to variation with frequency of the four primary constants of the cable and likewise there is a large number of equalizer sections for equalizing either the resistance and inductance of a cable or the capacity and leakage of a cable when the cable has a length short compared with the shortest wavelength transmitted. Any impedance which is suitable as a shunt arm for an equaliser for equalizing simultaneously the loss and phase can be used as an element in a chain for equalising leakage and capacity and any impedance suitable for use as a series arm for an equaliser for simultaneously equalising loss and phase can be employed as an element in a chain for equalising resistance and inductance.

The equaliser sections for equalising simultaneously the loss and phase due to variation with frequency of the four primary constants of the cable may be spaced at intervals along the length of the cable which are short compared with the shortest wavelength to be transmitted or, alternatively, an arbitrary length of cable may be equalised as a whole by a series of equaliser sections forming an artificial line disposed at any convenient point in the transmission system. The sections employed for equalising the resistance and inductance or the capacity and leakage may be disposed as stated above at intervals along the length of the cable or where artificial line type of equaliser sections are used for equalising the variations of resistance and inductance or capacity and leakage, such sections may be arranged as a whole at a convenient point in an arbitrary length of cable.

The elementary type of equaliser section referred to above with reference to Fig. 4, i. e., one composed of a series arm consisting of a condenser C_1 shunted by a resistance R_1 and a shunt arm composed of an inductance L_1 in series with a resistance R_2 is termed "an eight-

70

75

75

octave type", since it is found that its loss changes substantially from maximum to zero in about eight frequency octaves. The present invention contemplates the use of a modified form of section as shown in Figure 5, similar to the "eight-octave type" except that an additional condenser C_2 is inserted in shunt across the resistance R_2 of the shunt arm and an additional inductance L_2 is inserted in series with the resistance R_1 of the series arm, the resistance Z_0 being equal to the characteristic impedance of the section. With this modified form of section it is found that its loss falls from maximum to zero in only four octaves and, consequently, with the type of section shown in Figure 5 it is necessary to locate the sections up to only about two instead of four octaves above the highest frequency at which equalisation is required. With the four-octave section, therefore, less sections are required with the consequent reduction in dead loss produced by the equaliser and also a reduction in the amount of amplification required.

It will be appreciated that the sections described above may be replaced by their electrical equivalents. For example, in the elementary type of equaliser section composed of series and shunt arms the series arm may comprise a number of branches each formed by connecting a resistance in series with a capacity, these branches being shunted by two resistances in series whose joint is connected to the shunt arm, which comprises a resistance in series with a chain of parallel connected resistances and inductances.

In the practical application of the invention the characteristic curve of the cable to be equalised is first analysed either as a single component w^n or a series of such terms, the number of terms depending on the character of the curve. Over a large part of the range it may be found that $\omega^{1/2}$ fits the cable curve sufficiently well for practical purposes. The spacing factors appropriate to the values of n are calculated from the above expression for x substituting for a and t the values for the particular type of section being used. An equaliser for each of the ω^n components is then constructed and these are then assembled in series to form a complete equaliser of the artificial line type or the sections of the equaliser are distributed along the length of the cable as stated above.

Any errors due to cable distortion which might arise at very low frequencies where ωL is no longer large compared with R may be corrected by any suitable means.

Although in the specific embodiment of the invention described an electrical signal transmission system is referred to, it will be appreciated that the invention can also be applied to any wave transmission system in which similar difficulties are encountered due to the attenuation and phase of the transmission path and in which the path has properties analogous to those of resistance, inductance, capacitance and leakance. For example, in a long speaking tube for sound transmission its loss and phase distortion can be equalised in accordance with the invention. The acoustical waves transmitted may be transformed into their equivalent electrical oscillations by a suitable form of microphone, the necessary equalisation being then effected by an electrical equaliser.

It has also been suggested, in order to impart a time delay to electrical oscillations, to convert

the electrical oscillations into mechanical oscillations, as by applying the electrical oscillations to a piezo-electric crystal and to pass the mechanical waves through a trough containing fluid and to re-convert the mechanical waves transmitted through the liquid into electrical oscillations by a similar converting device, such as a piezo-electric crystal. The required time delay is produced in the transmission of the oscillations through the fluid. Undesirable loss and phase distortion will be introduced during the passage of the mechanical oscillations through the fluid, and the present invention can accordingly be applied for equalising this loss and phase. The equalisation is conveniently effected after the mechanical oscillations have been re-converted into electrical oscillations by employing an electrical equaliser of the kind hereinbefore described.

In the appended claims the quantities n , A_n and B_n referred to therein are magnitudes determined by an analysis of the characteristics of the cable, or line, which is to be equalised. Thus an analysis is made of the loss characteristic of the cable, or line, into the form of a power series in the frequency ω , of which a typical term is $A_n \omega^n$. The index n is different for each term, and if only the loss is to be equalised, n may assume any value less than 2; all that is necessary is that the sum of these power terms in ω shall represent with some degree of accuracy the loss characteristic of the line or cable. In the same way the phase characteristic may be analysed into the sum of a number of power terms $B_n \omega^n$. Here, however, equalisation cannot be effected if n is greater than unity. It will be appreciated therefore that if n is less than unity it may be possible to equalise both loss and phase simultaneously; this can be effected if relations such as

$$B_n = A_n \tan \frac{n\pi}{2}$$

hold between the coefficients A_n and B_n , conditions found to hold true in practice.

I claim:

1. A wave transmission system including a transmission path along which oscillations extending over a range of frequencies are caused to travel and in which range the attenuation of said path varies with the frequency ω as the sum of a number, including one, of terms given substantially by $A_n \omega^n$ and the phase delay of said path varies as the sum of a number, including one, of terms given substantially by

$$A_n \tan \frac{n\pi}{2} \omega^n$$

said variations causing distortions, and a compensating path associated with said transmission path comprising a number of groups, including one, of equaliser sections, one group to every pair of said terms $A_n \omega^n$ and

$$A_n \tan \frac{n\pi}{2} \omega^n$$

said sections of each group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said distortion due to variations of attenuation and phase delay of said transmission path.

2. A wave transmission system including a transmission path along which oscillations extending over a range of frequencies are caused to travel and in which range owing to the variation with frequency of the effective inductance and resistance of said path the attenuation of said path varies with the frequency ω as the sum of a number, including one, of terms given substantially by $A_n\omega^n$ and the phase delay of said path varies as the sum of a corresponding number, including one, of terms given substantially by

$$A_n \tan \frac{n\pi}{2} \omega^n$$

- 15 said variations causing distortions, and a compensating path associated with said transmission path comprising a number of groups, including one, of equaliser sections, one group to every pair of said terms $A_n\omega^n$ and

20 $A_n \tan \frac{n\pi}{2} \omega^n$

- the sections of each said group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said distortions due to variations of attenuation and phase delay of said transmission path due to said variation with frequency of the effective inductance and resistance of said path.

- 35 3. A wave transmission system including a transmission path along which oscillations extending over a range of frequencies are caused to travel and in which range owing to the variation with frequency of the effective capacity and leakance of said path the attenuation of said path varies with the frequency ω as the sum of a number, including one, of terms given substantially by $A_n\omega^n$ and the phase delay of said path varies as the sum of a corresponding number, including one, of terms given substantially by

$$A_n \tan \frac{n\pi}{2} \omega^n$$

- 50 said variations causing distortions, and a compensating path associated with said transmission path comprising a number of groups, including one, of equalizer sections, one group to every pair of said terms $A_n\omega^n$ and

55 $A_n \tan \frac{n\pi}{2} \omega^n$

- the sections of each said group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said distortions due to variations of attenuation and phase delay of said transmission path due to said variation with frequency of the effective capacity and leakance of said path.

4. A wave transmission system including a transmission path along which oscillations extending over a range of frequencies are caused to travel and in which range owing to the variation with frequency of the effective inductance, resistance, capacity and leakance of said path the attenuation of said path varies with the frequency ω as the sum of a number, including one,

of terms given substantially by $A_n\omega^n$ and the phase delay of said path varies as the sum of a corresponding number, including one, of terms given substantially by

$$A_n \tan \frac{n\pi}{2} \omega^n$$

said variations causing distortions, and a compensating path associated with said transmission path comprising a number of groups, including one, of equaliser sections, one group to every pair of said terms $A_n\omega^n$ and

$$A_n \tan \frac{n\pi}{2} \omega^n$$

the sections of each said group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said distortions due to variations of attenuation and phase delay of said transmission path due to said variations with frequency of the effective inductance, resistance, capacity and leakance of said path.

5. A wave transmission system including a transmission path along which oscillations extending over a range of frequencies are caused to travel and in which range the attenuation of said path varies with the frequency ω as the sum of a number, including one, of terms given substantially by $A_n\omega^n$, said variation causing distortion and a compensating path associated with said transmission path comprising a number of groups, including one, of equaliser sections, one group to every said term $A_n\omega^n$, the section of each said group having attenuation at certain reference frequencies equal to their attenuation at zero frequency multiplied by an arbitrary factor, these frequencies being so distributed as to correspond to substantially equal increments in the associated attenuation term, thereby substantially equalising said distortion due to variation of attenuation of said transmission path.

6. A wave transmission system including a transmission path along which oscillations extending over a range of frequencies are caused to travel and in which range owing to the variation with frequency of the effective inductance and resistance of said path the attenuation of said path varies with the frequency ω as the sum of a number, including one, of terms given substantially by $A_n\omega^n$, said variation causing distortion, and a compensating path associated with said transmission path comprising a number of groups, including one, of equaliser sections, one group to every said term $A_n\omega^n$, the sections of each said group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said distortion due to variation of attenuation of said transmission path due to said variation with frequency of the effective inductance and resistance of said path.

7. A wave transmission system including a transmission path along which oscillations extending over a range of frequencies are caused to travel and in which range owing to the variation with frequency of the effective capacity and leakance of said path the attenuation of

10 8. A wave transmission system including a transmission path along which oscillations extending over a range of frequencies are caused to travel and in which range owing to the variation with frequency of the effective inductance, resistance, capacity and leakance of said path the attenuation of said path varies with the frequency ω as the sum of a number, including one, of terms given substantially by $A_n\omega^n$, said variation causing distortion, and a compensating path associated with said transmission path comprising a number of groups, including one, of equaliser sections, one group to every said term $A_n\omega^n$, the sections of each group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said distortion due to variation of attenuation of said transmission path due to said variation with frequency of the effective inductance, resistance, capacity and leakance of said path.

15 9. A wave transmission system including a transmission path along which oscillations extending over a range of frequencies are caused to travel and in which range the phase delay of said path varies with the frequency ω as the sum of a number, including one, of terms given substantially by $B_n\omega^n$, said variation causing distortion, and a compensating path associated with said transmission path comprising a number of groups, including one, of equaliser sections, one group to every said term $B_n\omega^n$, the sections of each said group having phase delays at certain reference frequencies equal to a single arbitrary value, said reference frequencies being so distributed as to correspond to substantially equal increments in the associated phase delay term, thereby substantially equalising said distortion due to variation of phase delay of said transmission path.

20 10. A wave transmission system including a transmission path along which oscillations extending over a range of frequencies are caused to travel and in which range owing to the variation with frequency of the effective inductance and resistance of said path the phase delay of said path varies with the frequency ω as the sum of a number, including one, of terms given substantially by $B_n\omega^n$, said variation causing distortion, and a compensating path associated with said transmission path comprising a number of groups, including one, of equaliser sections, one group to every said term $B_n\omega^n$, the sections of

each said group having phase delays at certain reference frequencies equal to a single arbitrary value, said reference frequencies being so distributed as to correspond to substantially equal increments in the associated phase delay term, thereby substantially equalising said distortion due to variation of phase delay of said transmission path due to said variation with frequency of the effective inductance and resistance of said path.

25 11. A wave transmission system including a transmission path along which oscillations extending over a range of frequencies are caused to travel and in which range owing to the variation with frequency of the effective capacity and leakance of said path the phase delay of said path varies with the frequency ω as the sum of a number, including one, of terms given substantially by $B_n\omega^n$, said variation causing distortion, and a compensating path associated with said transmission path comprising a number of groups, including one, of equaliser sections, one group to every said term $B_n\omega^n$, the sections of each said group having phase delays at certain reference frequencies equal to a single arbitrary value, said reference frequencies being so distributed as to correspond to substantially equal increments in the associated phase delay term, thereby substantially equalising said distortion due to variation of phase delay of said transmission path due to said variation with frequency of the effective capacity and leakance of said path.

30 12. A wave transmission system including a transmission path along which oscillations extending over a range of frequencies are caused to travel and in which range owing to the variation with frequency of the effective inductance, resistance, capacity and leakance of said path the phase delay of said path varies with the frequency ω as the sum of a number, including one, of terms given substantially by $B_n\omega^n$, said variation causing distortion, and a compensating path associated with said transmission path comprising a number of groups, including one, of equaliser sections, one group to every said term $B_n\omega^n$, the sections of each said group having phase delays at certain reference frequencies equal to a single arbitrary value, said reference frequencies being so distributed as to correspond to substantially equal increments in the associated phase delay term, thereby substantially equalising said distortion due to variation of phase delay of said transmission path due to said variation with frequency of the effective inductance, resistance, capacity and leakance of said path.

35 13. A wave transmission system including a transmission path along which oscillations extending over a range of frequencies are caused to travel and in which range the attenuation of said path varies with the frequency ω as the sum of a number of terms given substantially by $A_n\omega^n$, and a compensating path associated with said transmission path comprising a number, including one, but less than said number of terms, of groups of equaliser sections, each said group corresponding to a single attenuation term given substantially by $A_n\omega^n$, the sections of each said group having attenuations at certain reference frequencies equal to their attenuation at zero frequency multiplied by an arbitrary factor, said reference frequencies being so distributed as to correspond to substantially equal increments in the associated attenuation term.

- tending over a range of frequencies are caused to travel and in which range the phase delay of said path varies with the frequency ω as the sum of a number of terms given substantially by 5 $B_n \omega^n$, and a compensating path associated with said transmission path comprising a number, including one, but less than said number of terms, of groups of equaliser sections, each said group corresponding to a single phase delay term. 10 given substantially by $B_n \omega^n$, the sections of each said group having phase delays at certain reference frequencies equal to a single arbitrary value, said reference frequencies being so distributed as to correspond to substantially equal increments in the associated phase delay term. 15

15. An electric wave transmission system, particularly for television, including a transmission path as exemplified by a cable and a transmission line, along which path oscillations extending over 20 a range of frequencies up to at least 100 kilocycles are caused to travel and in which range the attenuation of the path varies with the frequency ω as the sum of a number, including one, of terms given substantially by $A_n \omega^n$ and the 25 phase delay of said path varies as the sum of a corresponding number, including one, of terms given substantially by

$$A_n \tan \frac{n\pi}{2} \omega^n$$

- 30 said variations causing distortions, and a compensating path associated with said transmission path comprising a number of groups, including one, of equaliser sections, one group to every such pair of said terms $A_n \omega^n$ and 35

$$A_n \tan \frac{n\pi}{2} \omega^n$$

- the sections of each said group having attenuations at certain reference frequencies equal to 40 their attenuation at zero frequency multiplied by an arbitrary factor, said reference frequencies being so distributed as to correspond to substantially equal increments in the associated attenuation term, thereby substantially equalising simultaneously said distortions due to variations of 45 attenuation and phase delay of said transmission path.

16. An electric wave transmission system, particularly for television, including a transmission path as exemplified by a cable and a transmission line, along which path oscillations extending over a range of frequencies up to at least 100 kilocycles are caused to travel and in which range the attenuation of the path varies with the frequency ω as the sum of a number, including one, of terms given substantially by $A_n \omega^n$ and the phase delay of said path varies as the sum of a corresponding number, including one, of terms given substantially by 50

$$A_n \tan \frac{n\pi}{2} \omega^n$$

- and a compensating path associated with said transmission path comprising a number of groups, including one, of equaliser sections distributed at intervals along said transmission path, and one group to every such pair of said terms $A_n \omega^n$ and 65

$$A_n \tan \frac{n\pi}{2} \omega^n$$

- 70 the sections of each said group having attenuations at certain reference frequencies equal to their attenuation at zero frequency multiplied by an arbitrary factor, said reference frequencies being so distributed as to correspond to substan- 75

tially equal increments in the associated attenuation term, thereby substantially equalising simultaneously said variations of attenuation and phase delay of said transmission path.

17. An electric wave transmission system, particularly for television, including a transmission path as exemplified by a cable and a transmission line, along which path oscillations extending over a range of frequencies up to at least 100 kilocycles are caused to travel and in which range the attenuation of the path varies with the frequency ω as the sum of a number, including one, of terms given substantially by $A_n \omega^n$ and the phase delay of said path varies as the sum of a corresponding number, including one, of terms given substantially by 10 15

$$A_n \tan \frac{n\pi}{2} \omega^n$$

and a compensating path associated with said transmission path comprising a number of groups, including one, of equaliser sections, arranged to constitute an artificial line arranged in series with said transmission path, one group to every such pair of said terms $A_n \omega^n$ and 20 25

$$A_n \tan \frac{n\pi}{2} \omega^n$$

the sections of each said group having attenuations at certain reference frequencies equal to their attenuation at zero frequency multiplied by an arbitrary factor, said reference frequencies being so distributed as to correspond to substantially equal increments in the associated attenuation term, thereby substantially equalising simultaneously said variations of attenuation and phase delay of said transmission path. 30 35

18. A wave transmission system including a transmission path along which oscillations extending over a range of frequencies are caused to travel and in which range the attenuation of said path varies with the frequency ω as the sum of a number, including one, of terms given substantially by $A_n \omega^n$ and the phase delay of said path varies as the sum of a number, including one, of terms given substantially by 40 45

$$A_n \tan \frac{n\pi}{2} \omega^n$$

said variations causing distortion, and a compensating path associated with said transmission path comprising a number of groups, including one, of equaliser sections, one group to every pair of said terms $A_n \omega^n$ and 50

$$A_n \tan \frac{n\pi}{2} \omega^n$$

55 said sections of each group having attenuations at certain reference frequencies equal to their attenuation at zero frequency multiplied by an arbitrary factor, said reference frequencies being distributed so as to correspond to substantially equal increments in the associated attenuation term, said distortions due to variations of attenuation and phase delay of said transmission path being thereby substantially equalised simultaneously, said distribution being effected using an interval of loss equal to 60 65

$$n \int_0^\infty q^{n-1} f(q) dq$$

70 where $f(q)$ is the loss characteristic of a single section and q equals

$$\frac{P}{\omega}$$

75 P being said reference frequency of a section.

19. A wave transmission system including a transmission path along which oscillations extending over a range of frequencies ω are caused to travel, said oscillations being thereby distorted according to a frequency characteristic expressible as a number, including one, of terms of the form $X_n\omega^n$, and a compensating path comprising a number, including one, of groups of equaliser sections, each said group corresponding to one said term, the sections of each said group having frequency characteristics of like nature to said frequency characteristic and possessing at certain frequencies a given arbitrary value, said latter frequencies being so distributed as to correspond to equal increments in the said corresponding term, the distortion of said oscillations being thereby substantially reduced.

20. An electric wave transmission network for

simulating a desired frequency characteristic as exemplified by that of a transmission line, a cable, and a complement thereof, said frequency characteristic being expressible as a number, including one, of terms of the form $X_n\omega^n$ which comprises a number, including one, of groups of electrical networks, each said group corresponding to one said term, the networks of each said group having frequency characteristics of like nature to said desired frequency characteristic and possessing at certain frequencies a given arbitrary value, said latter frequencies being so distributed as to correspond to equal increments in the said corresponding term, the networks being so designed to provide a frequency characteristic which substantially simulates said desired characteristic.

JOHN COLLARD.
